APPARATUS FOR THE CONTROL OF HIGHWAY CROSSING SIGNALS

James J. Vanhorn, Swissvale, Pa., assignor to
The Union Switch & Signal Company, Swiss-
vale, Pa., a corporation of Pennsylvania

Original application January 11, 1936, Serial No.
58,716. Divided and this application October
27, 1936, Serial No. 107,848

5 Claims. (Cl. 246—130)

My invention relates to apparatus controlled by a train approaching a highway crossing for governing the operation of the highway crossing signal.

5 The present application is a division of my co-pending application Serial No. 58,716, filed January 11, 1936.

10 A feature of my invention is the provision of novel and improved apparatus controlled by a train approaching a highway crossing for preventing a continued operation of the highway crossing signal in the event the train should stop within the control section, and for restarting the operation of the signal when the train resumes 15 its movement. Other features and advantages of my invention will appear as the specification progresses.

20 I will describe one form of apparatus embodying my invention, and will then point out the novel features thereof in claims.

25 The accompanying drawing is a diagrammatic view of one form of apparatus embodying my invention wherein operation of a highway crossing signal is controlled by a train approaching the intersection from one direction only.

30 Referring to the drawing, the reference characters $1a$ and $1b$ designate the rails of a stretch of railway over which traffic normally moves in the direction indicated by the arrow, and which 35 rails are intersected by a highway H . A highway crossing signal S is located adjacent the intersection. This signal S may take any one of several different forms for highway crossing signals and, as here shown, is an audible signal in the form of an electric bell. The immediate control of signal S is effected through the medium of a control relay SC the arrangement being such that when relay SC is deenergized and its back contact 24 closed current is supplied to signal S 40 over a simple circuit and a warning is sounded. The manner of controlling the relay SC will be described hereinafter.

45 The track rails $1a$ and $1b$ are divided by insulated rail joints 2 to form three track sections $B3T$, $A3T$ and $2T$ which a train traverses in the order named in approaching the highway when traveling in the normal direction of traffic. As here shown, the exit end of section $2T$ is adjacent the highway H . The combined length of 50 these three track sections is sufficient to provide a desired warning period for the signal S prior to the arrival of a train at the intersection when operation of the signal is initiated as the train enters the section $B3T$. A wayside station 55 RWS , such for example as a passenger or freight

station, is associated with the track section $A3T$ and, as here shown, is near the junction of sections $A3T$ and $B3T$. Each track section is provided with a track circuit which includes a source of current such as a battery 3 connected across the rails at one end of the section, and a track relay R plus a prefix corresponding to the associated section connected across the rails at the other end of the section. 5

10 A track instrument designated by the reference character $M1$ is operatively connected with the rail $1b$ at a selected point for actuation thereof in response to the wheels of a train passing over the point at which the track instrument is located. This track instrument is so designed that 15 it has the characteristic of increasing its resistance in response to vibration of a train passing the location at which the instrument is attached to the rail. The track instrument $M1$ may take different forms and may be a rail microphone 20 such as disclosed and claimed in the Letters Patent of the United States No. 1,834,077, granted December 1, 1931 to A. J. Sorensen. It is deemed sufficient for the present application to point out that such rail microphone comprises an insulating 25 housing which contains two spaced metal electrodes with carbon granules in the space between the electrodes. When the microphone is not vibrated, the resistance between the electrodes through the carbon granules is relatively 30 low but when the microphone is vibrated by a passing train and the carbon granules are agitated the resistance between the electrodes becomes several times the normal resistance. It 35 will be understood, of course, that my invention is not limited to this one form of track instrument and other forms may be used. The track instrument $M1$ is located in the vicinity of the station RWS and as here shown is connected with the track rail near the exit of section $B3T$. The 40 track section $A3T$ is preferably short and track instrument $M1$ is vibrated while a train is moving in section $A3T$ as well as just prior to occupancy of section $A3T$. Although only one track instrument is shown, it will be understood that 45 additional instruments may be spaced along section $A3T$ and vibration of at least one instrument while a train is moving in the section is assured.

50 A relay D is controlled by the track instrument $M1$ and to that end is provided with a circuit 50 extending from the B terminal of any convenient source of current, such as a battery not shown, through the electrodes and carbon granules of the track instrument $M1$, winding of relay D and to the opposite terminal C of the same 55

source of current. The parts are so proportioned that when the track instrument M1 is at rest, the flow of current is sufficient to effectively energize relay D and its front contact 29 is closed, but when the track instrument is vibrated by a passing train the flow of current is reduced and the relay is deenergized, or at least is not sufficiently energized, and its front contact 29 is opened. Although only one track instrument is shown for controlling relay D, it will be understood that, if additional instruments are located at selected points along the track section A3T as pointed out hereinbefore, then such additional track instruments will be serially connected in the circuit of relay D.

The signal control relay SC is normally energized over a normally closed circuit passing from the terminal B of the current source over front contacts 25, 26, and 27 of track relays B3TR, 20 A3TR, and 2TR, respectively, winding of relay SC and to the opposite terminal C of the current source. An alternative energizing circuit for relay SC is provided which extends from the B battery terminal over front contact 25 of relay D, back contact 26 of relay A3TR, front contact 27 of relay 2TR, winding of relay SC and to the C battery terminal. It follows that when all three track sections 2T, 25 A3T and B3T are unoccupied and the track relays 2TR, A3TR and B3TR are picked up, or when the section A3T is occupied and section 2T is unoccupied and relay D is picked up, the relay SC is energized, but that when section 2T is occupied, or when section A3T is occupied and 30 relay D is down, or when section B3T is occupied and sections 2T and A3T are unoccupied, the relay SC is deenergized. The relay SC is made slightly slow to pick up in character, and consequently it will not pick up in response to pulsating energy which may be supplied to it by relay D momentarily picking up when a train in sections A3T and B3T is slowly passing over a track instrument.

When a train approaching the intersection enters section B3T, relay B3TR releases and at front contact 25 opens the normal energizing circuit for relay SC so that relay SC releases and closes its back contact 24 to start the operation of signal S. Just before the train enters section A3T, track instrument M1 becomes active and causes relay D to release and open a point in the alternative circuit for relay SC at front contact 29. As the train enters section A3T track relay A3TR releases, and at its back contact 26 closes a point in the alternative energizing circuit for relay SC and at its front contact 26 opens the normal circuit for relay SC. As stated hereinbefore, the track section A3T will be relatively short, or other track instruments 50 will be spaced along section A3T and interposed in the circuit for relay D in series with track instrument M1, and hence it will be apparent that so long as the train continues moving relay D will remain deenergized and operation of the signal S will continue, while the train is 55 passing through section A3T. When the train enters section 2T the relay 2TR will be released to open contact 27 interposed in both the normal and the alternative circuits of relay SC and operation of signal S will be effected until the train 60 passes over the intersection and vacates section 2T. If the train stops at the station RWS the relay D will pick up and close the alternative circuit for relay SC at front contact 29, to stop 65 the operation of the signal during the time the

train remains standing. The train, upon starting away from the station, will cause the track instrument to be vibrated with the result that relay D will be released, opening the alternative circuit of relay SC, and operation of the signal S will be started again. The operation will continue until the train passes over the intersection and vacates section 2T.

Although I have herein shown and described only one form of apparatus embodying my invention, it is to be understood that various changes and modifications may be made therein within the scope of the appended claims without departing from the spirit and scope of my invention.

Having thus described my invention, what I claim is:

1. In combination, a stretch of railway track divided into three track sections each provided with a track circuit including a track relay and one section of which is intersected by a highway, a highway crossing signal at the intersection, a track instrument associated with a rail of the intermediate of said sections and of a type which is actuated only by a moving train in its vicinity, 25 a normally energized control relay for said signal, a contact of the track relay of the section most remote from the intersection opened when a train approaches the intersection to effect the release of said control relay, a contact of the 30 track relay of the intermediate section opened when such section becomes occupied for preventing the reenergization of said control relay at such time, an auxiliary relay having an energizing circuit under the sole control of said track 35 instrument, and an energizing circuit for said control relay including contacts of the track relays of the intersected and intermediate of said sections and a contact of said auxiliary relay respectively.

2. In combination; a stretch of railway track divided into a first, a second and a third track section and each provided with a track circuit including a track relay; said first section intersected by a highway, a highway crossing signal 45 located at the intersection, a track instrument located at a station associated with said second and third track sections, an auxiliary relay controlled by said instrument and deenergized when a train is moving in the vicinity of the station, 50 a control relay for governing the operation of the signal, a normally closed circuit for said control relay and including a front contact for each of said track relays, and an alternative circuit for said control relay including a front contact of the auxiliary relay and a back contact of the track relay for the second section as well as a front contact of the track relay for the first section.

3. In combination; a stretch of railway track divided into a first, a second and a third track section and each provided with a track circuit including a track relay; said first section intersected by a highway, a highway crossing signal located at the intersection, a train actuated 65 means associated with the second section and actuated while a train is in motion in that section, an auxiliary relay controlled by said train actuated means and deenergized when said means is actuated, a control relay for governing 70 the operation of the signal, a normal circuit for said control relay including a front contact of each of said track relays, and an alternative circuit for said control relay including a front contact of the auxiliary relay and a back contact 75

of the track relay of the second sections as well as a front contact of the track relay for the first section.

4. In combination; a stretch of railway track divided into a first, a second and a third track section and each provided with a track circuit including a track relay; said first section intersected by a highway, a highway crossing signal located at the intersection, a station associated 10 with the second section, train actuated means associated with the track in the vicinity of the station and of the type which is actuated only by a moving train in the vicinity, an auxiliary relay controlled by said train actuated means and deenergized when said means is actuated, an operating circuit of said signal, means including a front contact of each of the track relays for modifying the condition of the operating circuit 15 as required to operate the signal in response to occupancy of any one of the three track sections, and other means including a front contact of the auxiliary relay and a back contact of the track relay of the second section to remove

such modified condition of the operating circuit while a train is standing at the station.

5. In combination; a stretch of railway track divided into a first, a second and a third track section and each provided with a track circuit including a track relay; said first section intersected by a highway and said second section relatively short, a highway crossing signal located at the intersection, a station located along the second section, a track instrument associated with a rail adjacent the junction of the second and third sections and of a type which is actuated only by a moving train in the vicinity, an auxiliary relay controlled by said track instrument, an operating circuit for the signal, means including a front contact of each of the track relays for modifying the condition of the operating circuit as required to operate the signal in response to occupancy of any one of the three track sections, and other means including a contact of said auxiliary relay to remove such modified condition of the operating circuit while a train is standing at the station.

JAMES J. VANHORN.
